COMBINED IRONING BOARD AND STEP LADDER

Filed Feb. 3, 1926

2 Sheets-Sheet 2

UNITED STATES PATENT OFFICE.

CHARLES DANIEL WOLF, OF PARIS, ILLINOIS.

COMBINED IRONING BOARD AND STEPLADDER.

Application filed February 3, 1926. Serial No. 85,734.

This invention relates to combined ironing boards and step ladders.

The object is to provide a strong and durable structure for domestic use which may be easily and quickly set up in the form of an ironing board rigidly mounted in the proper elevated position to be conveniently operated upon, said structure including means, when thus arranged, for supporting 10 a basket or other container beneath the ironing board and close to the floor in an accessible and yet out-of-the-way position, said supporting means being readily set up in position for use.

Another object is to provide a supplemental board to be used in connection with the main ironing board, for the purpose of ironing sleeves or other similar parts or articles of apparel, the same being easily 20 attached in position above and in spaced relation to the main board and at one end or the other thereof, as desired, the connection being such as to rigidly hold the sleeve board and prevent any relative movement thereof.

A further object is to provide means for supporting the clothes after they are properly ironed to preserve them in folded and creased condition, said means being in the form of a rack, which may be readily applied to the ironing board to provide a plurality of independently swingable arms movable into positions so as not to interfere with each other and over which the folded articles may be hung, the same being located at one 30 end of the ironing board and allowing ample space for the operator at either side of the same.

A still further object is to so construct and connect together the parts constituting 40 the ironing board, as to enable the same to be swung into position to form a convenient step ladder for domestic use, said ladder including the usual stile having a series of regularly spaced steps and rigidly supported by the ironing board, now constituting a strut, there being no projecting parts to interfere with the movements or the free use of the ladder, the structure being provided with means for securely housing and 45 holding the basket support, the sleeve ironing board and the clothes rack within the confines of the device when set up as a ladder, and the entire device being easily folded or closed into a flat form to be conveniently stored away when not in use.

A full and complete understanding of the

invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified, so long as 50 such changes or modifications mark no material departure from the salient features of the invention, as specifically pointed out in the appended claim.

In the drawings, in which similar reference characters designate corresponding parts throughout the several figures:—

Figure 1 is a perspective view of the structure set up as an ironing board.

Figure 2 is a vertical, longitudinal section through the same.

Figure 3 is a perspective view of the device converted into a step ladder.

Figure 4 is a detail section taken on the line 4—4 of Figure 2 and looking in the 55 direction indicated by the arrow.

Figure 5 is a detail section illustrating the means for housing the clothes rack upon the inner side of the ironing board.

Figure 6 is a detail perspective view showing the means for holding the basket stand in folded position.

The structure comprises a pair of spaced, elongated members 1, preferably formed of light, strong wood of a length and thickness to withstand the strain of ironing operations or to sustain the weight of a person, as said members are adapted to constitute the main supporting legs of the ironing board as well as the stiles of the step 60 ladder, when the structure is converted into such forms, and for convenience the said members will be hereinafter referred to as stiles.

The stiles 1 may be formed with parallel 100 side edges as shown in the drawings, or the same may taper from their upper to their lower ends if desired, the said lower ends being cut in an angular manner to provide different bearing surfaces 1^a and 1^b respectively, the surface 1^a resting upon the floor when the device is in use as an ironing board, while the other surfaces 1^b function likewise when in use as a step ladder.

At the upper ends the stiles 1 are angularly cut to receive an end board 2 and an upper or platform board 3, each being 105

curely nailed or otherwise secured in position to rigidly connect the two members together at this end, while the lower ends thereof are connected together by a board 5, spaced somewhat from the lower ends of the same and arranged at an angle thereto to constitute the lower step of the ladder.

At an intermediate point between the ends of the stiles 1, there is provided a transverse pivotal rod 5, the ends of which are suitably secured in the stiles somewhat nearer to their upper ends than to the lower ends thereof. Mounted to swing upon the pivotal rod is a supplemental frame having 15 side bars 6 bearing against the inner faces of the stiles, and joined together at their upper ends by a cross bar 7 arranged at an angle to the bars 6 and constituting the top step of the device when arranged as a step 20 ladder, as shown in Figure 3 of the drawing, the remaining steps 8 being mounted in between the side bars 6 in regular spaced relation and angularly thereto to coact with the lower step 4 carried by the stiles. The 25 supplemental frame, when swung about the pivotal rod 5, into crossed relation to the stiles, as shown in Figures 1 and 2, serves in conjunction with the latter to support the device as an ironing board, the lower ends 30 of the side bars 6 being formed at an angle to rest upon the floor, as do the faces 1^a of the said stiles.

Secured to the front edge of the top or platform board 3, as by means of ordinary 35 hinges 9, is an ironing board 10, the opposite, free end of which may be tapered in the usual manner, said board being adapted to be supported in elevated position over the floor by means of the hinged connections 40 with the stiles at one end, and by resting, at an intermediate point, upon the upper cross bar 7 of the supplemental frame.

The ironing board, as thus far described, resembles other foldable ironing boards for 45 domestic use, but the present invention contemplates the use, in connection therewith, of a detachable rack 10^a for holding the articles after they have been ironed, creased or folded in a manner to prevent damage, a detachable sleeve ironing board 11 and a foldable stand or support 12 for holding a basket or other container for washed clothes in an out of the way position off of the floor and under the ironing board 10.

55 The sleeve board 11 has its free end 11^a tapered to facilitate its introduction into sleeves or the like, and is held elevated above the main ironing board 10 by means of a pair of spaced, transverse cleats 13 secured 60 near the outer end thereof and adapted to rest upon the top face of the board 10. A metal strap 14 is secured to the sleeve board at its end, said strap having side bars 15 connected at their outer ends by a cross bar 16, 65 the said side bars 15 being adapted to slip

into longitudinally disposed, spaced slots 17 cut in from the free end of the ironing board 10, or into similar slots 18 formed at the other or hinged end of said board. When the bars 15 are thus engaged, the 70 cross cleats support the sleeve board elevated above the main board, and the transverse bar 16 bearing beneath the tongue portion formed between the slots 17 or 18, effectively prevents the sleeve board from rocking or moving.

In order to apply the sleeve board to the hinged end of the main board, the latter has its central portion cut out at the end, as indicated at 19, which permits the cross bar 16 80 of the holding strap to pass down together with the side bars 15 so that the latter may enter the slots 18 at that end and be held in position in the same manner, and in order to facilitate such action, the top or platform 85 board 3 is bevelled between the hinges 9, as shown at 20, thus permitting the bars 15 to rock slightly to introduce same into the slots 18 of the main board.

The board 10 is further provided with 90 spaced, longitudinally aligned sockets 21 formed at each end between the slots 17 and 18 respectively and the supporting cleats 13 of the sleeve board each has a depending pin 22 adapted to fit thereinto to further 95 anchor the sleeve board upon the main board.

When the device is arranged as an ironing board, with the stiles 1 and the supplemental frame in crossed relation, and the ironing board 10 resting upon the upper end of said supplemental frame, the tendency is for the latter to slide along the under face of the board away from the hinged end of the latter, and to prevent such movement 100 the board 10 is provided with an abutment in the form of a transverse cleat or strip 23 located adjacent to its center and adapted to bear against the top cross bar 7 of the supplemental frame and the strip 23 carries 105 a latch 7^a adapted to be swung into engagement with a headed stud 7^b on the cross bar 7 in order to prevent separation of the parts 7 and 23.

The cleat 23 is provided along its lower 110 face with an overhanging metal strip 24, the terminals of the overhanging portion being split to provide spring tongues 25, as more clearly shown in Figure 3 of the drawing. The cleat 23, together with the strip 24 having the tongues 25, terminate short of the side edges of the ironing board 10, and the latter also carries, near its outer, reduced end, another transverse cleat 26 which also terminates short of the tapered 120 side edges of the board, and is provided in its edge opposite to the cleat 23, with a socket or depression 27 over which extends a face plate 28 secured to the exposed face 125 of the cleat 26.

When the device is converted into the form of a ladder, as shown in Figure 3, or when it is desired to do ordinary ironing upon the main board 10, the sleeve board 5 may be housed and carried between the aforesaid cleats 23 and 26, with the large butt end of the sleeve board bearing against the cleat 23 and held from escape by the overhanging strip 24, the spring tongues 25 10 permitting the entrance of the end of the sleeve board by flexing the same outwardly and allowing the sleeve board to be slid in a transverse direction, after the other or pointed end of the sleeve board has been 15 placed within the aforesaid socket 27, as clearly shown in Figure 3.

The stiles 1 are provided adjacent to the aforesaid step 4, with longitudinally disposed slots 29 arranged somewhat nearer to 20 one edge of the stiles than to the other, and mounted to slide in said slots is a tie rod 30 having a head 31 at one end bearing against a washer contacting with the outer face of the adjacent stile, and at the other end being 25 provided with a thumb nut 32 which may bind the tie rod at any point along the opposed slots 29. The lower, free ends of the side bars 6 of the supplemental frame are slotted as at 33, and when the said frame is 30 swung to closed position to complete the step ladder, the tie rod 30 is loosened and moved upwardly to enter the said slots 33, whereupon the thumb nut may be tightened to rigidly hold the supplemental frame in 35 position, for use as a step ladder.

When the supplemental frame is folded within the stiles 1, and the main ironing board 10 acts as a strut for the step ladder, the said board is prevented from slipping 40 away from the ladder proper by a chain 34 having one terminal link secured to the pivotal rod 5 and carrying at its other end a hook 35 adapted to be engaged in an eye 36 carried by the aforesaid cleat 23 of the ironing board.

Mounted on the outer face of the end board 2 of the stiles, is a pair of spaced metal sockets 37 into which is adapted to be placed the depending side arms or posts 38 of a metal frame 39, the said sockets and posts being located adjacent to the ends of said end board, so that the frame is substantially as wide as the ironing board. The frame, together with the parts about to be 45 described, form a rack for receiving and supporting clothes, after the same have been ironed and folded or creased, and the side arms or posts are held together, intermediate of their lengths, by a connecting link or strap 40 which is adapted to rest upon the tops of the sockets 37 when the rack is in position for use.

Mounted on the side arms or posts 38, between the upper cross member of the frame 39 and the said connecting strap or link

40, are a plurality of coils 41 constituting terminal hubs of swingable rods or arms 42, formed of suitable rod iron, the said hubs bearing against each other and serving to hold the arms 42 in horizontal position upon the posts, and at the same time permitting the arms to be swung at any angle to be out of the way of the operator and to receive the folded clothes so as to avoid one piece interfering with another. 70

The ironing board 10 carries other spaced, transverse cleats 43 located at the hinged end thereof and spaced apart a sufficient distance to permit the clothes rack frame 39 to be placed therebetween, after the swinging arms 42 have been folded inwardly to overlap each other, as clearly shown in Figures 3 and 5. In order to prevent dislodgement of the rack frame, each cleat 43 is provided with an overhanging metal strip 44 80 beneath which the upper cross bar of the frame 39 and the terminals of the posts 38 of the clothes rack are adapted to be engaged, the ends of that strip 44 nearest to the aforesaid hinges 9 being formed into spring tongues 45 to prevent the frame from moving transversely of the ironing board and becoming dislodged from its seat. 90

The cleat 43 adjacent to the hinges 9 is 95 further provided with a passageway 43^a between its ends and flush with the under side of the ironing board 10, so as to permit the aforesaid cross bar 16 and supporting side bars 15 to pass therethrough and become fully seated at the ends of the aforesaid slots 18 at this end of the board 10. 100

The basket stand or support 12 hereinbefore mentioned comprises a U-shaped frame formed of stout bar or strip iron and having spaced side arms 46, the free terminals of which are independently pivoted to the inner faces of the stiles 1 by suitable pivot pins 47 and adapted to be folded down between the same. The outer ends of the arms 46 are joined by a cross bar 48 which, when the device is in use, is located substantially over the ends of the said stiles, and the U-shaped structure is further reinforced by suitable crossed braces 49 to sufficiently 110 strengthen the same. 115

In order to support the stand in a horizontal position to receive and hold a basket, tub or other receptacle containing the unironed clothes, legs 50 are employed, the same being formed of similar metal and pivoted at one end to the side arms 46 and adjacent to the swinging ends of the latter where connected by the member 48, said pivots being indicated at 51. The legs 50 are joined together intermediate of their ends, by a cross bar 52 so as to cause the same to be swung together, and the lower, free ends of said legs are adapted to rest upon foot plates 53 secured to the inner faces of the stiles 1 and close to the floor. 120 125 130

By folding the legs 50 upwardly and within the side arms 46 of the stand and then swinging the latter downwardly between the stiles, the whole structure is entirely housed 5 and out of the way to permit the same to be formed into a step ladder, and in order to hold the basket stand in such housed position, one of the side arms 46 is provided with an inwardly extending indentation to 10 provide a socket 54 adapted to snap over a lug or boss 55 formed in a metal plate 56 which is secured to the inner face of the adjacent stile 1.

From the foregoing it will be seen that the 15 several parts used in connection with the ironing board arrangement may be easily detached and stored within the confines of the structure to permit of the same being readily converted into step ladder form, or 20 folded flat into compact form for storing, and that the convenience of the foldable basket stand, as well as the universally movable clothes-supporting rack bars will be fully appreciated, as well as the advantage 25 of being able to mount the sleeve ironing board at one end of the main board or the

other to be most convenient for right or left hand persons.

What is claimed is:—

In a device of the class described, spaced 30 stiles joined together at their upper ends and having means for supporting the same in ladder form, and also having one or more steps at their lower ends, a supplemental frame intermediately pivoted to swing between the stiles, said frame having side bars and coacting steps, the side bars having open-ended slots in their lower ends, said stiles having longitudinal slots in position to align at their upper ends with the slots of 40 the frame when the latter is swung between the stiles, said longitudinal slots extending down below the lower ends of the side bars of the frame, and a tie rod having a head at one end and a thumb nut at the other end 45 and mounted in the longitudinal slots and adapted to be pushed up into the open-ended slots and the nut tightened to bind the supplemental frame in between the stiles.

In testimony that I claim the foregoing as 50 my own, I have hereto affixed my signature.

CHARLES DANIEL WOLF.
